VEHICLE

Richard H. Breidenich, Detroit, and Bernard N. Smith,
Oak Park, Mich., assignors to General Motors Corporation,
Detroit, Mich., a corporation of Delaware

Filed Nov. 12, 1964, Ser. No. 82,557

Term of patent 7 years

(Cl. D14—3)

FIGURE 1 is a side elevational view of a vehicle showing our new design;

FIGURE 2 is a top plan view;

FIGURE 3 is a front elevational view; and

FIGURE 4 is a rear elevational view.

The dominant features of our design reside in the full line portions of the drawings.

We claim:

The ornamental design for a vehicle, substantially as shown and described.
